LOOM SHUTTLE

Harold E. Goff, Millbury, Mass., assignor to
 Watson-Williams Manufacturing Company,
 Millbury, Mass., a corporation of Massachusetts

Application May 11, 1942, Serial No. 442,435

2 Claims. (Cl. 139—208)

This invention relates to shuttles used for weaving cloth, and relates more particularly to that type of shuttle in which the weft carrier or bobbin is placed on a spindle which is pivotally mounted in the shuttle. Spring means is commonly provided for holding the spindle in lowered and operative position, or in raised and inoperative position. It is essential that the spindle be accurately aligned with the shuttle-eye when in lowered position and it is desirable that the upward movement of the spindle be limited.

My present invention relates to the provision of improved means for accurately positioning a shuttle spindle in both operative and inoperative positions. My improved positioning means is so designed that all parts will permanently retain their desired relationship and that they will be strongly wear-resistant during long periods of use.

My invention further relates to arrangements and combinations of parts which will be hereinafter described and more particularly pointed out in the appended claims.

A preferred form of the invention is shown in the drawing, in which

Fig. 1 is a partial plan view of a shuttle embodying my improvements;

Fig. 2 is a sectional side elevation, taken substantially along the line 2—2 in Fig. 1;

Fig. 3 is a view similar to Fig. 2 but showing the spindle in raised and inoperative position;

Fig. 4 is a sectional elevation of certain parts, taken along the line 4—4 in Fig. 2;

Fig. 5 is a side elevation of a positioning block; and

Fig. 6 is a plan view thereof, looking in the direction of the arrow 6 in Fig. 5.

Referring to the drawing, I have shown a part of a shuttle S having the usual open body portion B to receive a bobbin or other weft carrier mounted on a spindle 10. The spindle 10 has a head 11 provided with an open bearing portion 12 adapted to fit over a fixed stud or pin 14 extending crosswise through the shuttle.

The spindle 10 preferably has a flange 15 which determines the inner or rearward position of the bobbin, and the head 11 of the spindle is provided with a relatively flat top surface 16 engaged by a holding spring 20 secured by a binding screw 21. The head 11 of the spindle 10 is mounted between the sides of a U-shaped retaining member 24 (Fig. 4) having an upturned flange 25 (Figs. 1 and 2) at its front edge adapted to be engaged by the flange at the butt

of a bobbin, which is thus held from accidental forward displacement.

All of the parts thus far described, except for the specific conformation of the head 11, are of the usual commercial type and in themselves form no part of my present invention, which relates to the accurate positioning of the spindle 10 in the operative position shown in Fig. 2 and also in the inoperative position shown in Fig. 3.

For the purposes of my invention, I provide the positioning block 30 shown in detail in Figs. 5 and 6 and having an inclined front surface 31, an upwardly extending lug 32, and a slightly inclined rear surface 33. The block 30 also has a transverse opening 34 to receive a cross pin or screw 35 when the block is mounted between the sides of the U-shaped retaining member 24.

The surfaces 31 and 33 are so disposed with respect to the surfaces 40 and 41 of the head 11 that they will accurately position the spindle, both in lowered and in raised position. When the spindle head surface 40 engages the stop surface 31 on the block 30, the spindle 10 will be accurately aligned with the shuttle eye as shown in Fig. 2, and when the rear surface 33 of the lug 32 is engaged by the surface 41 of the spindle head 11, the spindle is held in a desired raised position for removal and replacement of a bobbin or weft carrier. In both positions, the spring 20 engages the head 11 and yieldingly prevents return movement of the spindle until the spindle is forcibly displaced.

I have thus provided accurate and positive means for stopping the spindle in the desired raised and lowered positions, and I have also provided engaging surfaces of substantial area, so that they will not be affected by wear under any usual operating conditions. Consequently, the accurate positioning of the spindle in both operative and inoperative positions will be permanently maintained. The engaging surfaces 33 and 41 definitely prevent excess upward swinging movement of the spindle, when a bobbin is to be replaced.

It will be noted that upward movement of the spindle is stopped before the flange 15 can engage the end of the spring 20. Such engagement has been found capable of deforming or displacing the spring 20 in the shuttle, or it may split the end of the shuttle, in a shuttle where the spring 20 is not used.

Furthermore, I avoid the use of stop screws or other adjustable devices for positioning the spindle, which devices might become loosened or displaced during loom operation.

Having thus described my invention and the advantages thereof, I do not wish to be limited to the details herein disclosed, otherwise than as set forth in the claims, but what I claim is:

1. In a loom shuttle having a spindle with a spindle head and a fixed pivotal support for said spindle head in said shuttle, in combination, a positioning block, and means to secure said block in fixed position in said shuttle, said block having an inclined front end surface of substantial area coacting with a surface of similar area on said spindle head to locate said head in operative position, and said block having an upwardly extended lug with a rear surface coact-

ing with a second surface on the spindle head to limit upward swinging movement of said spindle.

2. The combination in a shuttle as set forth in claim 1, in which the spindle has a bobbin-engaging flange adjacent the spindle head, and in which the shuttle has a spring to yieldingly position the spindle in either operative or inoperative position, and in which swinging upward movement of the spindle to inoperative position is stopped by engagement of said lug and said second surface on the spindle head before said flange engages the front end of said spring.

HAROLD E. GOFF.
